CLAIM

The ornamental design for an electrically heated ice cream scoop, as shown and described.

DESCRIPTION

FIG. 1 is a front perspective view of an electrically heated ice cream scoop embodying the new design;

FIG. 2 is a front elevation view thereof;

FIG. 3 is a rear elevational view thereof;

FIG. 4 is a right side elevational view thereof;

FIG. 5 is a left side elevational view thereof;

FIG. 6 is a bottom plan view thereof; and,

FIG. 7 is a top plan view thereof.

The broken line shown in the drawings are for the purpose of illustrating unclaimed portions of the electrically heated ice cream scoop design and form no part of the claimed design.
